UNITED STATES PATENT OFFICE.

NATHANIEL B. SHALLENBERGER, OF SCOTTDALE, PENNSYLVANIA.

BURIAL-VAULT.

No. 859,014.

Specification of Letters Patent.

Patented July 2, 1907.

Application filed March 20, 1907. Serial No. 363,406.

To all whom it may concern:

Be it known that I, NATHANIEL B. SHALLENBERGER, a citizen of the United States, and a resident of Scottsdale, in the county of Westmoreland and State of Pennsylvania, have invented an Improvement in Burial-Vaults, of which the following is a specification.

My invention is an improvement in burial vaults, and consists in certain novel constructions and combinations of parts as will be hereinafter described and 10 claimed.

In the drawing, Figure 1 is a perspective view of a vault embodying my invention. Fig. 2 is a vertical longitudinal section thereof. Fig. 3 is a vertical cross section of the vault. Fig. 4 is a detail view illustrating the application of the rods for supporting the inner sealing plate; and Fig. 5 is a detail view of a portion of the inner sealing plate.

In carrying out my invention, I construct the vault with a body A, a cover B, an inner sealing plate C, 20 and rods D for supporting the plate C within the upper end of the body A as shown. The body A is provided with the upwardly projecting portion having the side plates A' and end plates A², and is also provided with the outwardly projecting flange E at its base, the said 25 flange being provided in its upper face with a continuous groove F extending entirely around the upwardly projecting portion of the body A, and having its outer wall F' tapered inwardly from its upper to its lower edge to form a beveled seat for the lower edge of 30 the depending flange G of the cover B. The upright portion of the body A is provided in the inner face of its side plates A' at their upper ends with notches or grooves a' which permit the insertion of the rods D after a casket has been placed in the body portion, the 35 said rods D extending above the casket and forming a support for the inner sealing plate C. This plate C, like the parts A and B, is preferably of concrete material, and has its edges leaded by a lead strip C', so that when inserted in the upper end of the upwardly projecting portion of the body plate, it will conform 40 closely to and fit snugly therein, aiding in the sealing operation, cement being applied around the edges of the plate C and especially to fill the slots or grooves a'. This plate C it will be noticed fits down within the 45 upper end of the body portion, and below the upper edges of the plates A' and A², leaving a recess into which projects the depending central portion B' of the cover B, the said cover B being grooved in its under face at B², forming the central depending portion B' 50 which projects down into the upper portion of the body A, and the depending side flange G fits down over the upwardly projecting portion of the body plate, and projects at its lower edges into the groove F and is beveled on its outer face at its said lower end at B⁴ to

coincide with the beveled seat F' on the body portion 55 when the parts are applied as shown in Figs. 2 and 3 of the drawing. The cover is reinforced in practice by a plate H of steel or other suitable metal, embedded therein and extending practically throughout the area of the cover terminating near the edges thereof, and 60 provided with threaded openings H' into which are threaded screw eyes I through which ropes for lowering the cover may be passed, and these screw eyes I may be removed after the cover is applied.

In the use of my invention, the body portion may 65 be placed in the grave, and the casket lowered thereinto, the rods D be applied, and the inner sealing plate C placed in position and cement applied over the plate C and around the edges thereof as before described, and cement be also applied in the groove F, after 70 which the cover may be lowered, the beveled seat B aiding in guiding the cover to its place, and forming with the cover and the cement a water tight joint entirely surrounding the body portion.

I claim:

75

1. A burial vault substantially as herein described, comprising in its construction a body having an upwardly projecting portion, whose side plates are grooved in their inner faces from their upper ends, and also provided with the outwardly projecting base flange having the groove in 80 its upper face, the outer wall of said groove being tapered forming a beveled seat, supporting rods fitted at their ends in the grooves in the inner faces of the side plates of the body, an inner sealing plate supported on said bars and arranged below the upper edge of the body forming 85 a recess, a marginal edge strip for said sealing plate, a cover fitting on the body portion and having in its lower face a groove receiving the upper edge of the body portion, and forming a central depending portion projecting within 90 the body portion, and an outer depending flange extending down along the outer side of the body portion, and projecting at its lower edge into the groove in the base flange, and tapered on its outer edge to conform to the beveled seat on the base flange, substantially as and for 95 the purposes set forth.

2. A burial vault comprising in its construction a body having an upwardly projecting portion whose inner side walls are formed in flat planes and provided in said flat planes with vertical grooves formed in the upper edges of the said inner side walls, side bars fitting at their ends in 100 said grooves and an inner sealing plate permanently supported on said side bars, substantially as set forth.

3. A burial vault comprising in its construction a body, an inner sealing plate fitting within the upper end of the body and having a marginal sealing strip to form a sealed joint within the body, and a cover fitting over the said plate and body, substantially as set forth.

4. A burial vault comprising in its construction a body, having a base flange grooved in its upper face, and having the outer wall of said groove tapered, forming a beveled 110 seat, and a cover fitting over the body portion, and having a depending flange projecting at its lower end into the groove of the base flange, and the beveled seat of the base flange, substantially as set forth.

5. A burial vault, comprising in its construction a body 115

having a laterally projecting base flange grooved in its upper face, and a cover grooved in its lower face to receive the upper edge of the body, and forming a depending central portion projecting within the body, the said cover being provided with a depending rim flange projecting at its lower edge in the groove in the upper face of the base flange, substantially as set forth.

6. A burial vault, comprising in its construction a body having an upwardly projecting portion, supporting bars

fitted removably within the said portion, a sealing plate 10 supported permanently on the said bars and having a marginal sealing strip to form a sealed joint within the body, and a cover, substantially as set forth.

NATHANIEL B. SHALLENBERGER.
